DESIGN FOR A COMBINATION CLIP SUPPORT AND COSMETIC CONTAINERS

Frank R. Prina, New York, N. Y.

Application April 4, 1941, Serial No. 100,129

Term of patent 7 years

To all whom it may concern:

Be it known that I, Frank R. Prina, a citizen of the United States and resident of New York city, in the county of New York and State of New York, have invented a new, original, and ornamental Design for a Combination Clip Support and Cosmetic Containers, of which the following is a specification, reference being had to the accompanying drawing, forming a part thereof.

Fig. 1 is a front elevational view of a combination clip support and cosmetic containers, showing my new design.

Fig. 2 is a side elevational view of the same.

Fig. 3 is a perspective view showing the back and bottom sides of Fig. 1.

Fig. 4 is a top plan view of the same.

I claim:

The ornamental design for a combination clip support and cosmetic containers, as shown.

FRANK R. PRINA.
